UNITED STATES PATENT OFFICE.

JOHN P. SJÖBERG, OF NEW YORK, N. Y.

DESIGN FOR A SASH-SPRING.

SPECIFICATION forming part of Design No. 27,894, dated November 23, 1897.

Application filed September 16, 1897. Serial No. 651,952. Term of patent 14 years.

To all whom it may concern:

Be it known that I, JOHN P. SJÖBERG, a citizen of the United States, residing at New York, in the county of New York and State 5 of New York, have invented and produced a certain new and original Design for Sash-Springs; and I do declare the following to be a full, clear, and exact description of the invention, such as will enable others skilled in 10 the art to which it appertains to make and use the same.

My invention has relation to a new and original design for sash-springs; and it consists of a spring of the configuration and ornamentation shown in the accompanying 15 drawings, in which—

Figure 1 is a perspective view. Fig. 2 is a longitudinal sectional view, and Fig. 3 is an edge view.

The leading features of my design consist 20 in a longitudinally-curved bar 1, the edges of which are parallel and the ends of which are bent at a slight angle to the body of the bar, one edge being provided intermediate its length with a lateral flat projection having a 25 rounded scalloped edge and a curved row of perforations, giving a crown-like appearance. This projection has not the curvature of the bar, but is straight.

What I claim is—

The design for a sash-spring, as herein shown and described.

In testimony whereof I hereunto affix my signature in presence of two witnesses.

JOHN P. SJÖBERG.

Witnesses:

ERNST L. FORSGREN,
FRED. WAHLSTROM.
